UNITED STATES PATENT OFFICE.

SAMUEL KRAUS, OF NEW YORK, N. Y., ASSIGNOR TO EAGLE PENCIL COMPANY, OF NEW YORK, N. Y.

DESIGN FOR A LEAD-PENCIL.

41,206.

Specification for Design.

Patented Feb. 28, 1911.

Application filed December 9, 1910. Serial No. 596,545. Term of patent 14 years.

To all whom it may concern:

Be it known that I, SAMUEL KRAUS, a citizen of the United States, and a resident of the city of New York, county and State of New York, have invented a new, original, and ornamental Design for Lead-Pencils, of which the following is a specification, reference being had to the accompanying drawing, forming a part thereof.

Figure 1 is a perspective view of a lead pencil exhibiting the design. Fig. 2 is an end elevation of the same.

The design consists of two sets of stripes *a* and *b* which follow a spiral path around the pencil from end to end thereof. The stripes *a* are spirally coiled in a direction

opposite to that in which the stripes *b* are coiled, so that the two intersect each other at regular intervals forming at their intersections diamond shaped figures *c*, which are bounded by the stripes. Each stripe *a* or *b* is composed of a plurality of parallel juxtaposed lines, impressed into the wood which forms the pencil sheath, and of a color contrasting with that of the sheath.

I claim—

The ornamental design for a lead pencil as shown and described.

SAMUEL KRAUS.
